ATTORNEY

UNITED STATES PATENT OFFICE.

STEVE M. GIRLICH, OF CHICAGO, ILLINOIS.

COMBINATION WINDOW GUARD AND DRAFT DEFLECTOR.

Application filed March 22, 1927. Serial No. 177,391.

This invention relates to certain novel improvements in combination window guards and draft deflectors and has for its principal object the provision of an improved 5 construction of this character which will be highly efficient in use and economical in manufacture.

Among the salient objects of the invention is to provide a window guard of the 10 character hereinafter described adapted to be supported by the sill of a window structure and function when thus supported to deflect the draft passing through the opening of the window structure provided by 15 raising the lower sash and to prevent dust and other particles of foreign matter from entering into the room through this opening and which occupies such a position upon the window sill as not to permit a child to 20 sit thereon when the lower window sash is in raised position.

Other objects will appear hereinafter.

The invention consists in the novel combination and arrangement of parts to be 25 hereinafter described and claimed.

The invention will be best understood by reference to the accompanying drawing, and in which:

Fig. 1 is an inside fragmentary elevational 30 view of a window structure showing my improved combination window guard and draft deflector associated therewith,

Fig. 2 is a sectional detail view of the same taken substantially on line 2-2 of 35 Fig. 1, and

Fig. 3 is a top plan view of the invention.

To better illustrate the application of my invention I have shown in the drawing a 40 window structure 10. This window structure 10 includes the side jambs 11 and sill 12. To this sill I associate my improved combination guard and draft deflector.

In the preferred form of construction the 45 invention includes two sections 13 and 14. Each section comprises a back wall 15 and a lateral wing 16 at one end thereof. The back wall 15 of the section 14 is adapted to adjustably overlap the back wall 15 of the 50 section 13 and these back walls are adjustably connected together through the medium of lips 18, one being formed on each back wall. The sections are further adjustably connected together through the medium of 55 a bar 19 secured to and extending from the wing 16 of the section 14. This bar 19 is

adjustably mounted between spaced bars 20. These spaced bars 20 have their corresponding end portions 21 connected to the wing 16 of the section 13 in any approved manner 60 and the inner of the bars 20 extend longitudinally with respect to the lower edge of the back wall 15 of the section 13 and is connected thereto in any approved manner. The opposite corresponding ends 22 of the 65 bars 20 are connected together through the medium of a plate 23 secured to these end portions through the medium of screw elements 24. The outer end portion of the bar 19 carries a plate 25 having its opposite 70 end portions 26 overlapping the bars 20 and functioning to guide the bar 19 with the co-operation of the plate 23 in its slidable movement between the bars 20.

Secured to the outer longitudinal edge of 75 the back wall 15 of the section 14 is a reinforcing strip 27, said reinforcing strip being secured to this back wall in any approved manner.

Connected to one end portion of this strip 80 and to the outer end portion of the back wall 15 of the section 13 are clamping elements 28 adapted for clamping engagement with the edge 29 of the sill 12 for detachably connecting the sections in draft deflecting 85 position.

From Fig. 2 it will be seen that when the combination guard and draft deflector is mounted upon the sill 12 the vertical edges 30 of the wings 16 engage the inner plate 90 11' of the side jambs 11 and the back walls 15 extend longitudinally with respect to the edge 29 of the sill 12, thus providing together with the sill, a substantial box-shaped compartment which is adapted to receive 95 the foreign particles entering through the opening 12' provided by raising the lower sash 13' of the window structure. As the draft enters this opening it strikes the back wall and any foreign particles carried therewith are deflected downwardly upon the sill 12 while the draft takes a course upwardly 100 toward the ceiling of the room.

By reason of the position occupied by my combination guard and draft deflector 105 it will be seen that a child cannot sit upon the sill when the window sash 13' is in raised position.

By making my improved guard and draft deflector adjustable it will be manifest that 110 the same may be associated with window structures of various widths.

While I have illustrated and described the preferred form of construction for carrying my invention into effect this is capable of variations and modifications without departing from the spirit of the invention. I, therefore, do not wish to be limited to the precise details set forth but desire to avail myself of such variations and modifications as come within the scope of the appended claims.

The invention having been set forth, what I claim as new and desire to secure by Letters Patent is:

1. In a device of the class described, two substantially L-shaped members, means for connecting the stem portion of said members together in slidable relation, spaced apart bars extending parallel to the stem portions of one of said members and suitably secured to the base portion thereof, a bar extending parallel to the stem portion of the other of said members and disposed between said spaced apart bars, and means for connecting said members in slidable relation.
2. A combination window guard and

draft deflector including two substantially L-shaped sections adapted to be disposed with the stem portions thereof arranged to extend upwardly at a right angle with respect to the outer longitudinal edge of a window sill and adapted to have the base portions thereof extended toward the frame of said window construction, means for connecting said stem portions whereby said stem portions are slidable relative to each other, a bracing member arranged along the lower edge of the outwardly disposed of said stem portions, substantially L-shaped members having the base portions thereof arranged below said sill and having the stem portions thereof adapted to be connected to said first named stem portions at the lower edges thereof adjacent the base portions, and securing members carried by said last named L-shaped strips adapted to engage the under side of said sill whereby to prevent displacement of said structure.

In testimony whereof I affix my signature.

STEVE M. GIRLICH.
